UNITED STATES PATENT OFFICE.

GUY G. SANDS, OF EAST GREENVILLE, PENNSYLVANIA.

SHUTTLE-OPERATING MECHANISM.

1,138,418.

Specification of Letters Patent.

Patented May 4, 1915.

Application filed March 10, 1914. Serial No. 823,706.

To all whom it may concern:

Be it known that I, GUY G. SANDS, a citizen of the United States, and a resident of East Greenville, in the county of Montgomery and State of Pennsylvania, have invented a new and Improved Shuttle-Operating Mechanism, of which the following is a full, clear, and exact description.

The invention relates to looms having a series of shuttles for simultaneously weaving a plurality of ribbons or other narrow ware.

The object of the invention is to provide a new and improved shuttle operating mechanism arranged to impart a positive and accurate movement to the shuttles without danger of breaking the operating straps.

In order to accomplish the desired result, use is made of a rack bar provided with a pin engaging a spiral groove formed in the peripheral face of a roller driven alternately in opposite directions by suitable means connected with the crank shaft.

A practical embodiment of the invention is represented in the accompanying drawings forming a part of this specification, in which similar characters of reference indicate corresponding parts in all the views.

Figure 1 is a side elevation of a loom of the type referred to and provided with the improved shuttle operating mechanism; Fig. 2 is an enlarged front elevation of the shuttle operating mechanism; and Fig. 3 is an enlarged front view of a modified form of the spiral groove in the roller.

The loom is provided with the usual lay A having a series of spaced shuttle races B in which are mounted to travel shuttles C alternately in opposite directions with a view to pass forward and backward through the open shed. Each of the shuttles C is provided with a rack D in mesh with the top of a pinion E journaled in the corresponding shuttle race B, and the said pinions E are in mesh at their bottoms with a rack F mounted to slide in suitable bearings arranged on the lay A. The rack F is provided near one end with a depending pin G engaging a spiral groove H formed in the peripheral face of the roller H' journaled in a bracket I attached to and depending from the lay A. The ends of the spiral groove H terminate in straight transverse grooves H², H³ so that when the roller H' is alternately turned in opposite directions then an intermittent reciprocating motion is

given to the pin G and the bar F whereby the latter turns the pinions E to cause the shuttle C to travel forward and backward through the open sheds. By having the straight ends H², H³ the shuttles C remain at rest for a short period at the end of each stroke, that is, during the time the lay beats up the filling and the harness changes the warp threads, and the lay returns to rear-most position to again open the sheds.

Suitable mechanism is employed for turning the roller H' alternately in opposite directions, such being, for instance, arranged as follows: On the roller H' is secured a gear wheel J in mesh with a gear wheel J' secured on a driving roller K journaled in the bracket I. To the peripheral face of the roller K are secured the upper ends of two bands L and L' extending from opposite sides of the roller K and passing around pulleys N, N' journaled on the stud N² held on the frame O of the loom (see Fig. 1). The lower ends of the bands L and L' are attached to the pivoted ends of an arm P secured on the shaft Q' of an elliptical gear wheel Q in mesh with a gear wheel R secured eccentrically on the crank shaft S of the loom and which crank shaft is connected by links T with the lay A to rock the latter in the usual manner. It will be noticed that when the loom is running a rocking motion is given to the arm P so that a pull is exerted alternately on the bands L, L' to turn the driving roller K alternately in the opposite direction. This turning action of the operating roller K is transmitted by the gear wheels J' and J to the roller H' whereby an intermittent reciprocating motion is given to the rack bar F and the shuttle C, as previously explained.

As shown in Fig. 2, the spiral groove H of the roller H' has a single convolution, but the spiral groove may consist of two or more convolutions, as indicated in Fig. 3. This construction is very serviceable in looms using large shuttles, and by providing two convolutions between the ends H², H³, the spiral groove is less abrupt and hence the pin G travels easier in the said spiral groove.

Having thus described my invention, I claim as new and desire to secure by Letters Patent:

1. A shuttle operating mechanism, comprising a shuttle having a rack, a rack bar, a pinion directly in mesh with the said shut-

tle rack and the said rack bar, a pin on the said rack bar, a roller having a spiral groove engaged by the said pin, the said spiral groove terminating in short transverse 5 grooves, and means operatively connected with the crank shaft of the loom for imparting a turning motion to the said roller alternately in opposite directions, and thereby give an alternate reciprocating motion to 10 the rack.

2. A shuttle operating mechanism, comprising a shuttle having a rack, a rack bar, a pinion in mesh with the said shuttle rack and said rack bar, a pin on the said rack bar, 15 a roller having a spiral groove engaged by the said pin, the said spiral groove terminating at each end in short transverse

grooves, a driving roller, gear wheels connecting the said grooved roller with the said driving roller, driving bands connected with the peripheral face of the said driving roller and extending from opposite sides thereof, an arm to which the said bands are secured, a shaft upon which said arm is secured, an elliptical gear on said shaft and engaged by 25 an eccentrically mounted pinion secured to the crank shaft of the loom.

In testimony whereof I have signed my name to this specification in the presence of two subscribing witnesses.

GUY G. SANDS.
